US00D907907S

(12) **United States Design Patent** (10) **Patent No.:** **US D907,907 S**
(45) **Date of Patent:** **** Jan. 19, 2021**

(54) **FOOTWEAR SOLE**

- (71) Applicant: **TBL Licensing LLC**, Stratham, NH (US)
(72) Inventors: **Kyle M. Jenkins**, Reading, MA (US); **Pierome Sar**, Stratham, NH (US); **Sam Grande**, Portsmouth, NH (US)
(73) Assignee: **TBL Licensing LLC**, Stratham, NH (US)
(**) Term: **15 Years**
(21) Appl. No.: **29/692,241**
(22) Filed: **May 23, 2019**

Related U.S. Application Data

- (60) Division of application No. 29/641,188, filed on Mar. 20, 2018, now Pat. No. Des. 850,083, which is a continuation-in-part of application No. 29/619,153, filed on Sep. 27, 2017, now Pat. No. Des. 831,317, which is a division of application No. 29/572,482, filed on Jul. 28, 2016, now Pat. No. Des. 812,882.

(57) **CLAIM**

The ornamental design for a footwear sole, as shown and described.

DESCRIPTION

This application is related to U.S. Design patent application Ser. No. 29/641,175, U.S. Design patent application Ser. No. 29/641,181, U.S. Design patent application Ser. No. 29/641,194, filed concurrently herewith and entitled "Footwear Sole," the entire disclosures of which, including the figures, are hereby expressly incorporated by reference herein.

FIG. 1 is a perspective view of a footwear sole in accordance with our design;

FIG. 2 is a front elevational view thereof;

FIG. 3 is a back elevational view thereof;

FIG. 4 is a left side elevational view thereof;

FIG. 5 is a right side elevational view thereof;

FIG. 6 is a top plan view thereof; and,

FIG. 7 is a bottom plan view thereof.

Broken lines are environmental only and form no part of the claimed design. Broken lines adjacent shaded areas of the design represent the bounds of the claimed design and are not themselves a part of the claimed design.

1 Claim, 7 Drawing Sheets
